[57] CLAIM

The ornamental design for an ergonomic bed sheet, as shown and described.

DESCRIPTION

FIG. 1 is a top plan view of a first embodiment of an ergonomic bed sheet embodying my design.

FIG. 2 is a cross-sectional view thereof, taken along line 2—2 of FIG. 1.

FIG. 3 is a top perspective view of the embodiment shown in FIG. 1.

FIG. 4 is a bottom plan view of the embodiment of FIG. 1.

FIG. 5 is a cross-sectional view thereof, taken along line 5—5 of FIG. 4.

FIG. 6 is a bottom perspective view of the embodiment shown in FIG. 1.

FIG. 7 is a top plan view of a second embodiment of an ergonomic bed sheet embodying my design.

FIG. 8 is a cross-sectional view thereof, taken along line 8—8 of FIG. 7.

FIG. 9 is a top perspective view of the embodiment shown in FIG. 7.

FIG. 10 is a top plan view of a third embodiment of an ergonomic bed sheet embodying my design.

FIG. 11 is a cross-sectional view thereof, taken along line 11—11 of FIG. 10; and,

FIG. 12 is a top perspective view of the embodiment shown in FIG. 10.
